UNITED STATES PATENT OFFICE.

ERNEST J. BRASSEUR, OF CHICAGO, ILLINOIS, ASSIGNOR TO A. B. DICK COMPANY,
OF CHICAGO, ILLINOIS, A CORPORATION OF ILLINOIS.

DUPLICATING MACHINE.

Application filed July 17, 1924. Serial No. 726,465.

To all whom it may concern:

Be it known that I, ERNEST J. BRASSEUR, a citizen of the United States, residing in the city of Chicago, county of Cook, and 5 State of Illinois, have invented certain new and useful Improvements in Duplicating Machines, of which the following is a specification.

This invention pertains to duplicating 10 machines and especially to the machines of this nature known as stencil duplicating machines. In particular the invention has to do with a new and novel inking means that eliminates the besmeared or unclean 15 conditions that have heretofore, in many instances, been attendant upon the inking operations, and to construct the improved inking means so that there will be an automatic even distribution of the ink as well 20 as providing for automatic recovery of excess ink.

The main object of this invention is to provide a duplicating machine with a new and improved inking means which gives a 25 substantially even distribution of ink, recovery of excess ink, absolute cleanliness and complete and satisfactory operating and printing results.

Another and important object of this 30 invention is to have portions of the novel inking means so constructed as to satisfactorily and efficiently maintain a quantity of free ink in close proximity to the stencil and to have this ink so held as not to cause 35 excessive inking in printing.

A further object of the invention is to provide such an improved inking means for machines of this type that the excess ink 40 will be automatically recovered into a suitable container or reservoir and thereafter to be readily usable. Also to so construct the inking means as to permit the recovery to take place during the operation of the machine.

Another object of this invention is to 45 construct the novel inking means so as to provide a continuous ink conveyor extending from the trailing end of the perforated diaphragm of such a machine to the leading 50 end of the diaphragm so that ink which leaves the diaphragm by reason of the rotation may be conducted back to the leading end of the diaphragm.

Another and important object of this in-

vention is to provide a duplicating machine 55 with a sealed compartment within which a supply of ink is held and maintained in operable condition and within which the inking operation and recovery of excess ink may efficiently take place thus preventing 60 the ink from reaching or flowing to places where it is not desired and thereby providing complete cleanliness which has not heretofore been possible in machines of this 65 nature.

Other objects and advantages of this invention will become apparent as a reading of the detailed description is continued.

Heretofore, in duplicating machines and especially in machines of the stencil duplicating type, there has been the disadvantage of uncleanliness due to the ink flowing to parts of the machine where it is not desired and often times reaching one or more places where it smears the paper which is being 75 printed. Also, very often, the operator performing the inking operation becomes besmeared and time is required to remove the ink and dirt from the operator's hands before proceeding with the other duplicating 80 operations. Thus much valuable time is lost. Also there has not heretofore been any satisfactory manner of evenly distributing the ink so that a continuously even intensity 85 of printing would be obtained.

By reason of the present novel structure and the operation of the same, the above mentioned disadvantages and other disadvantages have been eliminated and it now becomes possible to add ink to the operating 90 parts of the machine at any time, before or during operation thereof, to recover excess ink, and to perform these operations without having the ink reach undesirable places. Also, the ink becomes automatically distributed uniformly to a desired thickness, the excess being automatically recovered. Thus, 95 by reason of this construction, it becomes possible to invariably obtain printing or duplication work that is clear, definite and 100 of uniform intensity.

The preferred embodiment of this invention is herein illustrated in the accompanying drawings, wherein:

Fig. 1 is a perspective view of the drum 105 of a stencil duplicating machine partially broken away to show various elements of the improved inking means;

Fig. 2 is a vertical sectional view of the drum and parts of the frame taken on a line through the supporting axis;

Fig. 3 is a sectional view taken through the complete drum on the lines 3—3 of Fig. 2;

Fig. 4 is another sectional view of the drum taken on the line 4—4 of Fig. 2;

Fig. 5 is a top plan view of an open ink container or reservoir forming part of the inking means;

Fig. 6 is a view partially in section taken on the line 6—6 of Fig. 2;

Fig. 7 is a partial sectional view taken on the line 7—7 of Fig. 2;

Fig. 8 is a sectional view of the drum showing the perforated diaphragm in a definite position in relation to the ink reservoir, and;

Fig. 9 is another sectional view of the perforated diaphragm shown at another position in relation to the ink reservoir.

Referring now to these drawings, a drum 1 of a stencil duplicating machine is shown mounted on two upright standards 2 and 3 of a supporting frame. This drum is constructed to be rotated or driven by a suitable handle 4, or if desired a motor driving attachment may replace the handle 4.

The drum 1 is constructed in usual manner by providing plates 5 and 6 which are joined and held in position by a perforated diaphragm 7 and suitable connecting rods (not shown). The plates are provided with

the usual balance weights 8 and cam members 9 which control other parts of the duplicating machine. The diaphragm, as is usual in machines of this nature, carries a suitable inking pad 10 and stencil sheet 11 as noted in Fig. 1. Other well known features and parts of the duplicating machine are not shown and neither will they be particularly described except as they are involved in presenting the particular im-

proved inking means. It is however to be noted that the handle 4 drives the drum through suitable gears 12 and 13, this latter gear is provided with a lug 14 which engages pin 15 carried by plate 6 thereby transmitting the rotative power. In the construction herein shown it will be noted that the perforated diaphragm 7 is affixed, usually sealed as by solder or otherwise, to flanges 16 and 17 of the plates 5 and 6 respectively.

Other means for accomplishing this purpose may be employed if desired.

The preferred construction of apparatus employed in illustrating this invention may be readily appreciated by reference to Figs. 2, 3 and 4. In describing this novel inking means, it is first desired to locate or position all of the parts or elements of the means within the confines of the drum, and next to form a sealed compartment into which ink may be poured and thereafter all of the

inking operations may be performed within the compartment so that ink may not pass to parts of the machine where it is not desired. These features are considered to be broadly new.

In accomplishing the above purposes there is provided a shield 18 composed of a top portion 19 and side portions 20 and 21 which are affixed or sealed to the ends and edges of the perforated diaphragm 7 to form a sealed compartment. An opening 22 in shield 18 provides means for introducing ink into the compartment and a suitable screw cap 23 is employed to seal this opening. It is to be understood that the shield 80 may be of unit formation if desired, but it is found that the manufacturing and the assembly operations may be more quickly and easily accomplished by having the shield in separate portions. It will be noted from Fig. 2 that portions 20 and 21 engage the edges of the diaphragm. When desired, certain portions of the plates 5 and 6 may be employed to form parts of the compartment. For convenience of assembly 90 and repairs a relatively large opening 24 is provided in shield portion 21, and this opening is sealed over by a cover 25 after the assembly operations or repairs have been completed. See Figs. 2 and 3. This cover 95 is provided with an upturned tip 26 which is adapted to be received in an opening of a shaft which is rotated to remove the cover 25 from the sealed portions thereby permitting inspection and repairs.

With this sealed compartment as formed it will be noted that ink may be introduced through opening 22 on to the perforated diaphragm 7 and thereafter upon rotating the drum the ink will become distributed over the surface of the diaphragm and will pass through the diaphragm to the inking pad 10 and the stencil sheet 11. By reason of the cover portion 19 of the shield extending, in this preferred form, from one end of the diaphragm to the other, there is thereby formed a continuous conveyor for ink to pass from the trailing end of the perforated diaphragm to the leading end thereof. Thus during rotation of the drum any ink which passes from the end of the diaphragm will be conducted to the leading end thereof and thereby will again become useful. The formation of such a conveyor is one of the novel features of this improved inking means and is thought to be broadly new. The particular form of conveyor herein shown is only one form of apparatus for accomplishing this purpose, and it is understood that it is not essential that the conveyor form part of a sealed compartment.

It is desired, however, in making the inking means most efficient to provide a suitable means within the compartment for

holding a quantity of ink, and there is therefore provided a suitable container or reservoir 27 which receives ink as it is introduced through opening 22 and is constructed to later allow the ink to pass to the perforated diaphragm. The particular form of ink reservoir is clearly shown in Figs. 1, 2 and 5 and extends preferably the full width of the diaphragm. The preferred construction of the reservoir is in the nature of an open container having a portion thereof formed substantially on the arc of a circle and having the edges 28 and 30 bent inwardly as illustrated in Fig. 5 and provided with openings 31 which permit the ink to flow or pass to the perforated diaphragm in a predetermined manner so as to have a substantially equal distribution of ink across the diaphragm. The means for tipping the reservoir from a point outside of the sealed compartment will hereinafter be described in detail. In mounting the reservoir within the sealed compartment there is provided a suitable shaft 32 which is preferably mounted in end portions 20 and 21 of the shield 18. This mounting is such that the shaft does not rotate with the shield or the drum as will hereinafter be more particularly described.

From experience it is found that it is desirable in order to attain the greatest efficiency of the inking means to obtain a uniform distribution of the ink over the perforated diaphragm 7 in a manner which is preferably automatic. In addition, it is also found to be desirable to maintain a small quantity of ink in close proximity to the stencil sheet. The particular means herein disclosed for accomplishing these purposes comprises a suitable frame work hereinafter to be noted as grid 33, and to preferably provide this grid with longitudinal partitions 34 and cross partitions 35 which form relatively small areas or enclosures over the perforated diaphragm. It is desired to have these partitions so constructed with openings or to be particularly located so as to permit ink to flow from one area or enclosure to another. For this purpose there is provided suitable notches or openings 36 in the longitudinal partitions and the cross partitions are preferably located above the diaphragm. It is to be understood that the grid 33 may be placed in contact with the perforated diaphragm or it may be raised a trifle above, but in either position it is considered to be in close association with the perforated diaphragm. Preferably the grid is in contact with the diaphragm. For convenience of manufacturing and assembly the grid is divided into three sections which may be inserted through the opening 24 and placed in position. The middle section of the grid is provided with an opening which is received on pin 37

carried by an upright flange 38 mounted near one edge of the perforated diaphragm. All of the grid sections are preferably placed against this flange 38. A like flange 40 is positioned near the other edge of the diaphragm and is provided with an opening through which screw 41 passes into the middle section of the grid and thereby holds the same in desired position in relation to the perforated diaphragm. It will be noted by reference to Figs. 2 and 3 that the joining edges 42 and 43, and 44 and 45 of the sections are so formed at angles that the two end sections of the grid are automatically held in position between the flanges 38 and 40 and against the ends of the diaphragm or other suitable abutments.

It will be seen from the foregoing description that the ink which has been introduced through opening 22 into reservoir 27 may be passed from this reservoir through the openings 31 when the reservoir has been tipped. The openings 31 are so positioned that the ink will fall into the longitudinal channels of the grid as will be noted in Fig. 4. Also by reason of the cross partitions the distribution of the ink will be quickly accomplished across the width of the diaphragm. It is desired to have the drum rotated while the reservoir is tipped and thus permit the ink to be distributed between the longitudinal partitions for the length of the grid. The communicating notches 36 and the distances of the bottom edges on the cross partitions above the diaphragm will permit the ink to be spread to a substantially uniform thickness above the perforated diaphragm and across the whole area of the diaphragm. By reason of the particular construction of the grid a certain amount of the ink will adhere to the partitions and thus there is formed a small supply of the ink in close proximity to the stencil sheet. It is readily understood that the frame assists in maintaining this ink so that it does not pass through the perforations in the diaphragm too quickly and thus over-saturate the inking pad 10. It will be understood that the longitudinal and cross partitions may be constructed so as to provide areas of any particular desired dimensions for accomplishing the desired distribution and maintenance of a small supply of ink.

After the reservoir has been tipped to permit the ink to fall to the grid and to the perforated diaphragm and the drum rotated sufficiently to permit the distribution of the ink from one end of the diaphragm to the other, the drum may be rotated at an increased speed thereby causing the ink to spread out and automatically distribute itself in uniform manner over the diaphragm.

In constructing this novel inking means

so as to efficiently and automatically recover excess ink, any suitable arrangement may be made. It is preferable to construct the shield 18 and the reservoir 27 so that part 46 of the top portion 19 of the shield will be formed in substantially an arc of a circle and to so position this part in respect to the non-rotating reservoir that it will pass one edge of the reservoir with a very small clearance. It will be noted from Figs. 3 and 4 that the cover portion 19 of the shield is sealed to the ends of the perforated diaphragm. Preferably these ends are upturned to form abutments 47 and 48 which are provided with openings 50. It will now be clearly seen that when the drum is rotated the excessive ink will pass from the perforated diaphragm through openings 50 along the cover portion 19 of shield 18 to the substantially semi-circular part 46 and a material portion of this ink will be caught by the edge of the reservoir and will thus be recovered back into the reservoir. The remainder of the ink will pass on to the leading end of the diaphragm. Thus, excess ink on the perforated diaphragm will be automatically recovered into the reservoir. It is to be noted that this recovering operation will be accomplished during the regular operation of the duplicating machine.

From this preferred construction of the improved inking means as hereinbefore described, it will be noted from Figs. 8 and 35 9 that the machine may be left with the drum in any particular position without injury and when positioned with the perforated diaphragm uppermost the ink will quickly return to the reservoir as it is found 40 that it will drop from the partitions as will be especially noted in Fig. 8 instead of having to flow along the diaphragm to the ends thereof and then along the shield and into the reservoir. With this improved construction 45 there will be a direct and quick recovery of the ink when the diaphragm is positioned in its normal non-operating position.

It will be seen that the shield, grid and reservoir all cooperate to create the most 50 efficient inking means that gives a uniform distribution of ink over the diaphragm, that maintains a suitable small supply of ink on the diaphragm and that automatically recovers excess ink. The grid automatically 55 operates and controls the amount of ink held on the perforated diaphragm. In the normal operations of the machine a platen engages the paper to be printed and holds the paper against the stencil. Normally this 60 platen exerts quite a force to press the stencil against the diaphragm and in so doing if the ink pad is saturated the ink is forced back into the areas or enclosures and the movement of the drum causes the excess ink to pass to the shield where it is re-

covered into the reservoir. Thus, all of the elements of the inking means cooperate to attain a very high efficiency.

It is well understood in machines of this nature that when the ink is maintained with- 70 in a sealed enclosure that atmospheric temperatures and pressures affect the ink and often times cause parts of the apparatus to sweat or to otherwise manifest an unnormal condition within the compartment. 75 Since in the herein preferred construction there is provided a sealed compartment, it is found desirable to provide suitable ventilation. In accomplishing this purpose there is provided a central opening 51 in the shaft 32 which supports ink reservoir 27 and a suitable collar 52 carried by the shaft 51 carries a ventilating pipe 53 which takes the form of a shepherd's crook so that the ink will not seal the opening. This simple 80 ventilating means provides a suitable air inlet and outlet which maintains the pressure within the sealed compartment satisfactory and at the same time does not permit such a radical change of air that is 85 detrimental to the ink. Any other suitable means of accomplishing this purpose may be incorporated when desired, but this means has been satisfactory in its operation.

The particular mechanical construction 95 which is herein provided for performing the operation of tipping the reservoir preferably consists of a shaft 54 mounted in standard 3 and which is provided with a suitable handle 55 for oscillating the same through 100 a definite length of travel as between stops 56 and 57. (See Fig. 7.) The pin 58 is mounted in the shaft 54 and is movable with the handle 55 to engage the stops. The left hand end of shaft 54 is provided with a lug 105 60 which engages a suitable slot 61 formed in the end of shaft 32 as may be readily noted by reference to Figs. 2 and 6. In assembling the shaft 32 and the reservoir 27 the ventilating pipe 53 must come into correct position to the tipping handle 55 as there is provided a suitable bolt 62 which passes through the lower portion of the slot 110 61 thereby requiring that the lug 60 be inserted in slot 61 in only one position. There is provided a suitable spring 63 which has one end in engagement with the shaft 54 and the other end in engagement with a shaft 65 which functions to support the drum on the standard 3. This spring causes the reservoir to be automatically returned to its normal position after it has been tipped to permit the ink to flow to the perforated diaphragm. Thus it will be seen that the reservoir within the sealed compartment may 120 be tipped at will from a point outside of the compartment. Other constructions may be employed to accomplish this purpose but the present apparatus has been satisfactory.

In the construction of the sealed compart- 130

ment, it has been found from experience that it is desirable to provide end wells in the walls of the sealed compartment so that as the drum is taken from the machine and placed on either end or in any position other than horizontal that the ink within the compartment will not pass out of the compartment to undesirable places in the machine. To form these end wells there is provided offset portions 66 and 67 in the shield 18. These end wells are of sufficient width or depth to receive the usual quantity of ink, which may be in the reservoir in addition to the ink held on the perforated dia-

15 phragm, in such a manner as to prevent the ink from leaking through the diaphragm and flooding the edges of the stencil sheet and ink pad. It will be noted that upstanding flanges 38 and 40 form with the offsets 66 and 67 respectively unobstructed channels so that as the drum is again mounted in the standards and rotated or brought back to the horizontal, the ink in the end well will quickly pass to the semicircular portion 46 of the shield and will be recovered into the reservoir and from which it may again be passed on to the perforated diaphragm.

20 It will be seen from the foregoing description that the cap 23 may be removed and ink placed in the reservoir 27. Usually the reservoir is of such size as to receive a full pound of ink. The ink then within a sealed compartment is maintained in good operating condition by reason of the ventilating

25 means, but it is not subjected to a flow of air thereover which always tends to deteriorate the ink. The operations of normally distributing the ink on the perforated diaphragm and for recovering excess ink have 30 already been described in detail and it will not therefore be necessary to go further into detail. It will be noted from the above outline of the parts of the improved inking means that all of the inking operations are 35 performed within a sealed compartment and that it is possible to recover excess ink and that a suitable quantity of ink is always in close proximity to the stencil sheet in such a manner as to admit of substantially 40 uniform intensity of printing. It will also be noted that when any portion of the stencil sheet appears to be drying by not having a sufficient quantity of ink, the drum may be rotated to desired position and the ink 45 reservoir tipped from a point exterior of the drum to pass ink to the point of the perforated diaphragm which is not properly supplied with ink. Thus, with only a moment's hesitation in the normal operation 50 of the machine, ink may be supplied to any points which do not appear to have sufficient quantity of ink. This improved inking means, therefore, provides for all the inking operations being carried on within a 55 properly ventilated sealed compartment, and

as so constructed duplicating operations may be carried on from day to day without necessitating a series of preparatory inking operations before the machine will produce satisfactory duplicating work of substantially uniform intensity of printing. 70

It will be understood that while there is here described in detail a particular embodiment of the invention for purposes of full disclosure, and some detailed features which are specifically claimed for a special advantage, many changes and modifications may be made in the particular construction and arrangement of parts without departing from the broad scope of the invention which is outlined in the subjoined claims. 75

What I claim is:

1. In a duplicating machine the combination of a stencil carrying drum, a perforated diaphragm carried by said drum and constructed to receive ink which passes to a stencil, and a cover means mounted within the confines of said drum and being constructed to form a portion of a sealed compartment within which the inking operation of said machine is performed, said diaphragm being arranged to form a portion of said compartment, said cover means and said diaphragm forming a sealed compartment that encloses a support mounted substantially in the axis of said drum, the cubical volume of said compartment being less than that of said drum. 85

2. In a duplicating machine, the combination of a stencil carrying drum, a perforated diaphragm carried by said drum and constructed to form part of the circumference thereof, and means associated with said diaphragm to form a sealed compartment therewith, said compartment being sufficiently large to enclose a support mounted substantially in the axis of said drum, the cubical volume of said compartment being less than that of said drum. 100

3. In a duplicating machine, the combination of a stencil carrying drum, a perforated diaphragm carried by said drum and constructed to form part of the circumference thereof, a shield associated with said diaphragm to form a sealed compartment therewith, a separate ink carrying receptacle mounted within said compartment, said receptacle adapted to be tipped to release ink therefrom. 115

4. In a duplicating machine, the combination of a stencil carrying drum, a perforated diaphragm carried by said drum, a shield associated with said diaphragm to form a sealed compartment therewith, said shield being carried within the confines of said drum and being of such size as to make the cubical volume of said compartment greater than one half but less than the whole of the cubical volume of said compartment, and an ink reservoir mounted 120

within said compartment, said reservoir being non-rotatable in respect to said drum and said shield.

5. In a duplicating machine, the combination of a stencil carrying drum, a perforated diaphragm carried by said drum, a shield associated with said diaphragm to form a sealed compartment therewith, and an ink reservoir held within said compartment and being non-rotatable in respect to said drum and said shield, said reservoir being positioned to be tipped to permit ink to flow to said diaphragm.

6. In a duplicating machine, the combination of a stencil carrying drum, a perforated diaphragm carried by said drum, a shield associated with said diaphragm to form a sealed compartment therewith, a reservoir mounted within said compartment 20 for holding ink and adapted to be tipped to permit the ink to flow to said diaphragm, and means for distributing the ink over said diaphragm.

7. In a duplicating machine the combination of a stencil carrying drum, an ink reservoir positioned within the confines of said drum and constructed to free ink on to said diaphragm, and means firmly affixed in association with said diaphragm for assisting in 30 distributing ink over said diaphragm.

8. In a duplicating machine the combination of a stencil carrying drum, a perforated diaphragm carried by said drum, a grid positioned in contact with said diaphragm for assisting in distributing ink over said diaphragm and for maintaining a small supply of ink thereon, and a reservoir mounted within the confines of said drum for holding a supply of ink.

40 9. In a duplicating machine the combination of a stencil carrying drum, a perforated diaphragm carried by said drum, a grid positioned in contact with said diaphragm for assisting in distributing ink over said diaphragm and for maintaining a small supply of ink thereon, said grid being partitioned to form relatively small enclosed areas, and having openings in the partitions of said grid to permit ink to flow from one 45 area to another, and a reservoir mounted within said drum for holding a supply of ink.

10. In a duplicating machine, the combination of a stencil carrying drum, a perforated diaphragm carried by said drum, an ink carrying receptacle mounted within the confines of said drum, and a grid juxtaposed to said diaphragm for assisting in distributing the ink thereover.

60 11. In a duplicating machine, the combination of a stencil carrying drum, a perforated diaphragm carried by said drum, an ink reservoir mounted within the confines of said drum and constructed to be tipped to free ink on to said diaphragm, and

a grid means positioned in proximity to said diaphragm for controlling the distribution of ink thereover.

12. In a duplicating machine, the combination of a stencil carrying drum, a perforated diaphragm carried by said drum and constructed to receive ink which passes to a stencil, a cover means mounted within the confines of said drum and being constructed to form a portion of a sealed compartment within which the inking operation of said machine is performed, said diaphragm being arranged to form a portion of said compartment, and means juxtaposed to said diaphragm and being non-movable in respect thereto for assisting in distributing ink over said diaphragm.

13. In a duplicating machine the combination of a stencil carrying drum, a perforated diaphragm carried by said drum, a shield carried by said drum and being sealed with said diaphragm to form a sealed compartment within which inking operations are performed, and means placed in proximity to said diaphragm and being non-movable in respect thereto for maintaining a small supply of ink substantially uniformly distributed over said diaphragm.

14. In a duplicating machine, the combination of a stencil carrying drum, a perforated diaphragm carried by said drum, a shield carried by said drum and being sealed to said diaphragm to form a sealed compartment within which inking operations are performed, and a grid mounted within said compartment and in close relation to said diaphragm for assisting in the distributing of ink placed on said diaphragm.

15. In a duplicating machine the combination of a stencil carrying drum, a perforated diaphragm carried by said drum, a shield carried by said drum and being sealed to said diaphragm to form a sealed compartment within which inking operations are performed, and a grid positioned to have parts thereof in contact with said diaphragm for controlling the distribution of ink over said diaphragm and for maintaining a small supply of ink thereon.

16. In a duplicating machine the combination of a stencil carrying drum, a perforated diaphragm carried by said drum, a shield carried by said drum and being sealed to said diaphragm to form a sealed compartment within which inking operations are performed, and a grid positioned partially in contact with said diaphragm for assisting in distributing ink over said diaphragm and for maintaining a small supply of ink thereon, said grid being partitioned to form relatively small enclosed areas.

17. In a duplicating machine the combination of a stencil carrying drum, a perforated diaphragm carried by said drum, a shield carried by said drum and being sealed to

- 5 said diaphragm to form a sealed compartment within which inking operations are performed, and a grid positioned in contact with said diaphragm for controlling the distribution of ink over said diaphragm and for maintaining a small supply of ink thereon, said grid being partitioned to form relatively small enclosed areas and having openings in the partitions of said grid to permit 10 ink to flow from one area to another.
18. In a duplicating machine the combination of a stencil carrying drum, a perforated diaphragm carried by said drum, a shield also carried by said drum and constructed to form a sealed compartment with said diaphragm, said shield being carried within the confines of said drum and being of such size as to make the cubical volume of said compartment greater than one half 20 but less than the whole of the cubical volume of said compartment, and a tipable non-rotating reservoir mounted within said compartment for holding a supply of ink.
19. In a duplicating machine the combination of a stencil carrying drum, a perforated diaphragm carried by said drum and adapted to receive an ink pad and a stencil sheet, and a shield sealed to said diaphragm thereby forming a compartment 30 therewith and within which compartment ink may be maintained irrespective of the position of said drum, said shield being carried within the confines of said drum and being of such size as to make the cubical volume of said compartment greater than one half but less than the whole of the cubical volume of said compartment.
20. In a duplicating machine, the combination of a stencil carrying drum, a perforated diaphragm carried by said drum and constructed to form part of the circumference thereof, and a shield associated with said diaphragm to form a sealed compartment therewith, said shield being provided 40 with end wells to receive the ink within said compartment when said drum is placed on either end.
21. In a duplicating machine, the combination of a stencil carrying drum, a perforated diaphragm carried by said drum, and a shield carried by said drum and being sealed to the edges and ends of said diaphragm for forming a sealed compartment therewith, said shield being carried within 50 the confines of said drum and being of such size as to make the cubical volume of said compartment greater than one half but less than the whole of the cubical volume of said compartment.
22. In a duplicating machine, the combination of a stencil carrying drum, a perforated diaphragm carried by said drum, and a shield carried by said drum and being sealed to the edges and ends of said diaphragm for forming a sealed compartment 60 therewith, said shield being provided with wells in each side thereof for receiving the ink within said compartment when said drum is moved into horizontal position.
23. In a duplicating machine, the combination of a stencil carrying drum, a perforated diaphragm carried by said drum and forming part of the circumference thereof, a shield associated with said diaphragm to form a sealed compartment 70 therewith, said shield being provided with end wells to receive the ink within said compartment when said drum is placed on either end, and a non-rotating ink reservoir mounted within said shield.
24. In a duplicating machine, the combination of a stencil carrying drum, a perforated diaphragm carried by said drum and forming part of the circumference thereof, a shield associated with said diaphragm to form a sealed compartment therewith, said shield being provided with end wells to receive the ink within said compartment when said drum is placed on either end, a non-rotating ink reservoir 80 mounted within said shield, and a grid positioned within said compartment and in proximity to said diaphragm for assisting in the inking operation performed within said compartment.
25. In a duplicating machine, the combination of a stencil carrying drum, a perforated diaphragm carried by said drum and constructed to form part of the circumference thereof, a shield associated with said diaphragm to form a sealed compartment therewith, said shield being provided with end wells to receive the ink within said compartment when said drum is placed on either end, a non-rotating ink reservoir 90 mounted within said shield, and a grid positioned within said compartment and in proximity to said diaphragm for assisting in the inking operation performed within said compartment.
26. In a duplicating machine, the combination of a stencil carrying drum, a perforated diaphragm carried by said drum and constructed to form part of the circumference thereof, and a shield associated with said diaphragm to form a sealed compartment therewith, a non-rotating ink reservoir 100 mounted within said shield, and a grid positioned within said compartment and in juxtaposition to said diaphragm for assisting in distributing ink over said diaphragm, said grid being partitioned to form small enclosed areas for maintaining ink 110 in predetermined relation to said diaphragm.
27. In a duplicating machine the combination of a stencil carrying drum, a perforated diaphragm carried by said drum and forming part of the circumference thereof, a shield associated with said diaphragm to form a sealed compartment therewith, a non-rotating ink reservoir 115 mounted within said shield, and a grid positioned within said compartment and in proximity to said diaphragm, said grid being partitioned to form small areas for controlling distribution of ink and for maintaining ink in predetermined relation with said diaphragm, said grid partitions being provided with openings which permit ink to flow from one area to another.
28. In a duplicating machine the combination of a stencil carrying drum, a perforated diaphragm carried by said drum and forming part of the circumference thereof, a shield associated with said diaphragm to form a sealed compartment 120 therewith, a non-rotating ink reservoir mounted within said shield, and a grid positioned within said compartment and in proximity to said diaphragm, said grid being partitioned to form small areas for controlling distribution of ink and for maintaining ink in predetermined relation with said diaphragm, said grid partitions being provided with openings which permit ink to flow from one area to another.
29. In a duplicating machine the combination of a stencil carrying drum, a perforated diaphragm carried by said drum and forming part of the circumference thereof, a shield associated with said diaphragm to form a sealed compartment 125 therewith, a non-rotating ink reservoir mounted within said shield, and a grid positioned within said compartment and in proximity to said diaphragm, said grid being partitioned to form small areas for controlling distribution of ink and for maintaining ink in predetermined relation with said diaphragm, said grid partitions being provided with openings which permit ink to flow from one area to another.

nation of a stencil carrying drum, a perforated diaphragm carried by said drum, and an open ink reservoir carried by said drum and being non-rotatable therewith, 5 said reservoir being constructed to permit ink to flow to said diaphragm.

28. In a duplicating machine the combination of a stencil carrying drum, a perforated diaphragm carried by said drum, 10 and an open ink reservoir carried by said drum and being non-rotatable therewith, said reservoir adapted to be tipped to permit ink to flow to said diaphragm.

29. In a duplicating machine, the combination of a stencil carrying drum, a perforated diaphragm carried by said drum, an open ink reservoir carried by said drum and being non-rotatable therewith, said reservoir adapted to be tipped to permit 15 ink to flow to said diaphragm, and means associated with said reservoir for tipping the same, said means being operable from a point outside of said drum.

30. In a duplicating machine, the combination of a stencil carrying drum, a perforated diaphragm carried by said drum, and an open reservoir mounted within the confines of said drum and adapted to be tipped to pour ink on to said diaphragm, 25 said reservoir having a portion of its exterior formed in the arc of a circle and having a length substantially equal to the width of said drum.

31. In a duplicating machine, the combination of a stencil carrying drum, a perforated diaphragm carried by said drum, an open reservoir mounted within the confines of said drum and adapted to be tipped to pour ink on to said diaphragm, said 35 reservoir having a portion of its exterior formed in the arc of a circle and having its edges bent inwardly and providing the edges with openings through which ink passes to predetermined portions of said diaphragm when said reservoir is tipped.

32. In a duplicating machine, the combination of a stencil carrying drum, a perforated diaphragm carried by said drum, an open reservoir mounted within the confines of said drum and adapted to be tipped to pour ink on to said diaphragm, said reservoir having a portion of its exterior formed in the arc of a circle, the length of said reservoir being substantially equal 50 to the width of said drum, the edges of said reservoir being bent inwardly and being provided with openings through which ink passes on to the diaphragm when said reservoir is tipped, and means exterior of said drum for tipping said reservoir.

33. In a duplicating machine, the combination of a stencil carrying drum, a perforated diaphragm carried by said drum, a shield associated with said diaphragm for forming a compartment therewith, and an 55

open reservoir mounted within said compartment for holding ink and being non-rotatable in relation to said drum.

34. In a duplicating machine, the combination of a stencil carrying drum, a perforated diaphragm carried by said drum, a shield associated with said diaphragm for forming a compartment therewith, an open reservoir mounted within said compartment for holding ink and being non-rotatable in 70 relation to said drum, and means operable on the outside of said compartment for tipping said reservoir to cause the ink to flow on to said diaphragm.

35. In a duplicating machine the combination of a stencil carrying drum, a perforated diaphragm carried by said drum, a shield affixed to said diaphragm in a manner to form a sealed compartment therewith, and a non-rotating ink reservoir mounted 75 within said compartment, said shield being offset to pass around said reservoir as said drum is rotated.

36. In a duplicating machine, the combination of a stencil carrying drum, a perforated diaphragm carried by said drum, a shield associated with said diaphragm for forming a compartment therewith, and an open reservoir mounted within said compartment for holding ink and being non-rotatable in relation to said drum, said reservoir having an exterior portion thereof constructed substantially in the arc of a circle. 95

37. In a duplicating machine, the combination of a stencil carrying drum, a perforated diaphragm carried by said drum, a shield associated with said diaphragm for forming a sealed compartment therewith and an open reservoir mounted within said compartment for holding ink and being non-rotatable in relation to said drum, said shield being formed to have a portion thereof of pass in close proximity to one edge of said reservoir as said drum is rotated. 100

38. In a duplicating machine, the combination of a stencil carrying drum, a perforated diaphragm carried by said drum, a shield associated with said diaphragm for forming a sealed compartment therewith, and an open reservoir mounted within said 105 compartment for holding ink and being non-rotatable in relation to said drum, said shield having a portion thereof formed substantially in the arc of a circle to pass around said reservoir as said drum is rotated and to pass in close proximity to an edge of said reservoir.

39. In a duplicating machine, the combination of a stencil carrying drum, a perforated diaphragm carried by said drum, a shield associated with said diaphragm for forming a compartment therewith, and an open reservoir mounted within said compartment for holding ink and being non-rotatable in relation to said drum, said reservoir 115

- voir having an exterior portion thereof constructed in the arc of a circle, said shield having a portion thereof formed substantially in the arc of a circle to pass around 5 said reservoir in close proximity thereto.
40. In a duplicating machine the combination of a stencil carrying drum, a perforated diaphragm carried by said drum, a shield also carried by said drum and being 10 sealed to said diaphragm to form a compartment therewith, a shaft mounted in said shield, and an ink reservoir carried by said shaft and being so mounted as to be non-rotatable in respect to said drum.
- 15 41. In a duplicating machine the combination of a stencil carrying drum, a perforated diaphragm carried by said drum, a shield also carried by said drum and being 15 sealed to said diaphragm to form a compartment therewith, a shaft mounted in said shield and in the line of the axis of said drum, and an ink carrying reservoir mounted on said shaft and adapted to be non-rotatable with said shield.
- 20 42. In a duplicating machine the combination of a stencil carrying drum, a perforated diaphragm carried by said drum, a shield also carried by said drum and being 20 sealed to said diaphragm to form a compartment therewith, a shaft mounted in said shield and in the line of the axis of said drum, an ink carrying reservoir mounted on said shaft and adapted to be non-rotatable with said shield, said reservoir being 25
- 30 constructed to be tipped to permit ink to flow to said diaphragm, and means exterior of said compartment for tipping said reservoir.
- 35 43. In a duplicating machine the combination of a stencil carrying drum, a perforated diaphragm carried by said drum, a shield also carried by said drum and being 35 sealed to said diaphragm to form a compartment therewith, a shaft mounted in said shield, an ink carrying reservoir mounted on said shaft and adapted to be non-rotatable with said shield, said reservoir being 40 constructed to be tipped to permit ink to flow to said diaphragm, means exterior of 40 said compartment for tipping said reservoir, and means for limiting the extent to which 45 said reservoir may be tipped.
44. In a duplicating machine, the combination of a stencil carrying drum, a perforated diaphragm carried by said drum, a shield also carried by said drum and being 50 sealed to said diaphragm to form a compartment therewith, a shaft mounted in said shield, an ink carrying reservoir mounted 50 on said shaft and adapted to be non-rotatable with said shield, said reservoir being 55 constructed to be tipped to permit ink to flow to said diaphragm, operating means exterior of said compartment for tipping said reservoir, means for limiting the extent 60 to which said reservoir may be tipped, and 60 spring means for returning said reservoir to its normal position after it has been tipped.
45. In a duplicating machine the combination of a stencil carrying drum, a perforated 70 diaphragm carried by said drum and arranged to receive ink, and a shield affixed to the ends of said diaphragm for allowing ink to pass from the trailing end of said diaphragm to the leading end thereof as said 75 drum is rotated.
46. In a duplicating machine the combination of a stencil carrying drum, a perforated diaphragm carried by said drum and arranged to receive ink, a shield affixed to the ends of said diaphragm for allowing ink to pass from the trailing end of said diaphragm to the leading end thereof as said 80 drum is rotated, and an ink reservoir carried by said drum for supplying ink to said diaphragm. 85
47. In a duplicating machine, the combination of a stencil carrying drum, a perforated diaphragm carried by said drum, means for inking said diaphragm, and means for recovering excess ink from said 90 diaphragm.
48. In a duplicating machine, the combination of a stencil carrying drum, a perforated diaphragm carried by said drum and constructed to receive ink, and means for recovering excess ink flowing from said diaphragm, said means being operable to recover ink during the operation of said machine. 95
49. In a duplicating machine, the combination of a stencil carrying drum, a perforated diaphragm carried by said drum, a shield associated with said diaphragm, and ink reservoir carried by said drum and being 100 non-rotatable therewith, said shield being 100 constructed to receive excess ink passing from said diaphragm, said reservoir constructed to have one edge thereof positioned in close proximity to a portion of said shield during a part of the travel of said shield to 110 thereby recover excess ink back into said reservoir. 110
50. In a duplicating machine, the combination of a stencil carrying drum, a perforated diaphragm carried by said drum, an open ink reservoir mounted within said drum and constructed to be tipped to have 115 ink pass therefrom to said diaphragm from over one edge of said reservoir, and means associated with said reservoir and said diaphragm for receiving excess ink flowing from said diaphragm and for passing the same back into said reservoir. 120
51. In a duplicating machine, the combination of a stencil carrying drum, a perforated diaphragm carried by said drum, an open ink reservoir mounted within said drum and constructed to be tipped to have 125 ink pass therefrom to said diaphragm from over one edge of said reservoir, and means 130

associated with said reservoir and said diaphragm for receiving excess ink and for returning the same to said reservoir over another edge of said reservoir.

- 5 52. In a duplicating machine the combination of a stencil carrying drum, a perforated diaphragm carried by said drum and arranged to receive ink, a shield affixed to the ends of said diaphragm for allowing ink to 10 pass from the trailing end of said diaphragm to the leading end thereof as said drum is rotated, and an ink reservoir carried by said drum and being non-rotatable therewith and having an edge which is passed by a portion 15 of said shield in close proximity as said shield is rotated by the rotation of said drum to thereby recover into said reservoir a predetermined amount of ink on said shield.

53. In a duplicating machine the combination of a stencil carrying drum, a perforated diaphragm carried by said drum and adapted to receive an ink pad and a stencil sheet, a shield sealed to the edges and ends of said diaphragm to form a sealed compartment 25 therewith, and an ink reservoir mounted within said compartment and being non-rotatable in respect to said drum, said shield and said reservoir being constructed to have a portion of said shield pass in close proximity to one edge of said reservoir to thereby permit excess ink on said shield to be recovered into said reservoir.

54. In a duplicating machine, the combination of a stencil carrying drum, a perforated diaphragm carried by said drum and adapted to receive an ink pad and a stencil sheet, a shield sealed to the edges and ends of said diaphragm to form a sealed compartment therewith, and an ink reservoir mounted 40 within said compartment and being non-rotatable in respect to said drum, said shield and said reservoir being constructed to have a portion of said shield pass in close proximity to one edge of said reservoir to thereby permit excess ink on said shield to be recovered into said reservoir, said shield being provided with end wells for receiving ink from said reservoir and from said diaphragm when said drum is tipped or placed 45 on either end.

55. In a duplicating machine, the combination of a stencil carrying drum, a perforated diaphragm carried by said drum, a shield sealed to the edges and ends of said 55 diaphragm to form a sealed compartment therewith, an ink reservoir mounted within said compartment, said shield being provided with end wells for receiving ink when said drum is placed on either end, said shield and said reservoir being constructed and mounted to have said reservoir non-rotatable and to have said shield pass in close proximity to said reservoir when said drum is rotated to thereby recover ink from said 60 shield into said reservoir, and channels 65

formed along the edges of said diaphragm and extending to the top portion of said shield to permit relatively rapid flow of ink to said top portion of said shield where it is recovered into said reservoir.

70

56. In a duplicating machine, the combination of a stencil carrying drum, a perforated diaphragm carried by said drum, means for inking said diaphragm, means cooperating with said inking means for recovering excess ink flowing from said diaphragm, and means for holding a predetermined amount of ink in close proximity to said diaphragm.

75

57. In a duplicating machine the combination of a stencil carrying drum, a perforated diaphragm carried by said drum, means for inking said diaphragm, means cooperating with said inking means for recovering excess ink, and a grid positioned in close proximity to said diaphragm for assisting in distributing ink over said diaphragm and for maintaining a predetermined amount of ink on said diaphragm, the excess ink flowing from said diaphragm and automatically passing to said ink recovering means.

80

58. In a duplicating machine, the combination of a stencil carrying drum, a perforated diaphragm carried by said drum, means for inking said diaphragm, means cooperating with said inking means for recovering excess ink from said diaphragm, and a grid engaging said diaphragm for assisting in distributing ink thereover, said grid being partitioned to form small enclosed areas, said partitions being provided with openings for permitting ink to pass from one area to another.

95

59. In a duplicating machine, the combination of a stencil carrying drum, a perforated diaphragm carried by said drum, a shield affixed to the ends and edges of said diaphragm and being sealed therewith to form a sealed compartment, an ink reservoir mounted within said compartment and having a portion thereof formed in the arc of a circle and extending substantially across said diaphragm, said reservoir being non-rotatable in respect to said drum, and a grid mounted in engagement with said diaphragm for substantially uniformly distributing thereover the ink received from said reservoir.

105

60. In a duplicating machine, the combination of a drum adapted to be rotated, a perforated diaphragm extending circumferentially for a portion of the distance around said drum, a shield carried by said drum and being sealed to the ends and edges of said diaphragm to form a sealed compartment therewith, an ink reservoir mounted within said compartment but not rotatable with said drum, said reservoir being suspended to be tipped to allow ink to flow to 110

110

115

120

125

130

- said diaphragm, and a grid mounted in engagement with the inner surface of said diaphragm and constructed to allow ink to flow along and across said diaphragm.
- 5 61. In a duplicating machine, a drum, a perforated diaphragm forming part of said drum and being adapted to receive ink and a frame constructed with a plurality of relatively small open areas, said frame being 70 normally positioned in close proximity to said diaphragm to assist in distributing some of the ink over said diaphragm and to support some of the ink to give an even supply thereof on said diaphragm, said 75 frame positioned to permit ink to flow therebeneath and above said diaphragm.
- 10 62. In a duplicating machine, a drum, a perforated diaphragm forming part of said drum and being adapted to receive ink, and a frame constructed with a plurality of relatively small open areas, said frame being normally positioned in close proximity to said diaphragm and having more than two points thereof in contact with said diaphragm for supporting said frame in the predetermined relation to said diaphragm, said frame being positioned to permit ink to flow therebeneath and above said diaphragm, said frame operating to assist in 80 distributing some of the ink over said diaphragm and to support some of the ink to give an even supply thereof on said diaphragm.
- 15 63. In a duplicating machine the combination of a stencil carrying drum, a perforated diaphragm carried by said drum and constructed to receive ink which passes to a stencil, a cover means mounted within the confines of said drum and being constructed to form a portion of a sealed compartment within which the inking operation of said machine is performed, said diaphragm being arranged to form another portion of said compartment, and means for ventilating said 85 sealed compartment.
- 20 64. In a duplicating machine, the combination of a stencil carrying drum, a perforated diaphragm carried by said drum, a shield sealed to said diaphragm to form a compartment therewith, and means for ventilating said compartment.
- 25 65. In a duplicating machine, the combination of a stencil carrying drum, a perforated diaphragm carried by said drum, a shield sealed to said diaphragm to form a compartment therewith, and means for ventilating said compartment, said means constructed to prevent ink from entering an air opening in said ventilating means.
- 30 66. In a duplicating machine, the combination of a stencil carrying drum, a perforated diaphragm carried by said drum, a shield affixed to said diaphragm to form a sealed compartment therewith, a shaft mounted within said shield and in line with 90 the axis of said drum, an ink carrying reservoir mounted on said shaft and being non-rotatable in respect to said drum, a ventilating pipe carried by said shaft at a point within said compartment, said shaft having an opening communicating with the opening in said pipe and leading to the exterior of said drum for permitting the passage of small quantities of air to and from the interior of said compartment.
- 35 67. In a duplicating machine, the combination of a stencil carrying drum, a perforated diaphragm carried by said drum, a shield affixed to said diaphragm to form a sealed compartment therewith, an open ink reservoir mounted within said compartment and constructed to cooperate with a portion of said shield to recover excess ink which flows from said diaphragm, and means for ventilating the interior of said compartment.
- 40 68. In a duplicating machine, the combination of a stencil carrying drum, a perforated diaphragm carried by said drum, a shield affixed to said diaphragm to form a sealed compartment therewith, an open ink reservoir mounted within said compartment and constructed to cooperate with a portion of said shield to receive excess ink which flows from said diaphragm, a grid associated with said diaphragm for distributing ink 95 thereover to a substantially uniform thickness, and means for maintaining the atmospheric pressure within said compartment substantially equal to the pressure of the external atmosphere.
- 45 69. In a duplicating machine, the combination of a stencil carrying drum, a perforated diaphragm carried by said drum, a shield associated with said diaphragm to form a sealed compartment therewith, an open ink reservoir mounted within said compartment and being non-rotatable in respect to said drum, means extending to the exterior of said compartment for tipping said reservoir to permit ink to flow to said diaphragm, and means for ventilating the interior of said compartment.
- 50 70. In a duplicating machine, the combination of a stencil carrying drum, a perforated diaphragm carried by said drum, a grid mounted on said diaphragm and partitioned into relatively small areas, said grid being provided with openings to permit ink to flow from one area to another, a shield engaging the ends and edges of said diaphragm and being sealed thereto to form a sealed compartment, an open ink reservoir mounted within said compartment and extending substantially the full width thereof, said reservoir being non-rotatable in respect 100 to said drum and being mounted to permit ink to fall to said diaphragm in a predetermined manner, said reservoir cooperating with a part of said shield to recover excess ink which passes from said diaphragm, and 105
- 55 71. In a duplicating machine, the combination of a stencil carrying drum, a perforated diaphragm carried by said drum, a grid mounted on said diaphragm and partitioned into relatively small areas, said grid being provided with openings to permit ink to flow from one area to another, a shield engaging the ends and edges of said diaphragm and being sealed thereto to form a sealed compartment, an open ink reservoir mounted within said compartment and extending substantially the full width thereof, said reservoir being non-rotatable in respect 110 to said drum and being mounted to permit ink to fall to said diaphragm in a predetermined manner, said reservoir cooperating with a part of said shield to recover excess ink which passes from said diaphragm, and 115
- 60 72. In a duplicating machine, the combination of a stencil carrying drum, a perforated diaphragm carried by said drum, a grid mounted on said diaphragm and partitioned into relatively small areas, said grid being provided with openings to permit ink to flow from one area to another, a shield engaging the ends and edges of said diaphragm and being sealed thereto to form a sealed compartment, an open ink reservoir mounted within said compartment and extending substantially the full width thereof, said reservoir being non-rotatable in respect 120 to said drum and being mounted to permit ink to fall to said diaphragm in a predetermined manner, said reservoir cooperating with a part of said shield to recover excess ink which passes from said diaphragm, and 125
- 65 73. In a duplicating machine, the combination of a stencil carrying drum, a perforated diaphragm carried by said drum, a grid mounted on said diaphragm and partitioned into relatively small areas, said grid being provided with openings to permit ink to flow from one area to another, a shield engaging the ends and edges of said diaphragm and being sealed thereto to form a sealed compartment, an open ink reservoir mounted within said compartment and extending substantially the full width thereof, said reservoir being non-rotatable in respect 130 to said drum and being mounted to permit ink to fall to said diaphragm in a predetermined manner, said reservoir cooperating with a part of said shield to recover excess ink which passes from said diaphragm, and

means for ventilating the interior of said compartment.

71. In a duplicating machine, the combination of a stencil carrying drum, a perforated diaphragm carried by said drum, a grid mounted on said diaphragm and partitioned into relatively small areas, said grid being provided with openings to permit ink to flow to adjacent areas, a shield engaging the ends and edges of said diaphragm and being sealed thereto to form a sealed compartment, an open ink reservoir mounted within said compartment and extending substantially the full width thereof, said reservoir being non-rotatable in respect to said drum and being mounted to permit ink to fall to said diaphragm, said reservoir having a portion thereof formed substantially in the arc of a circle, said shield having a portion thereof also formed substantially in the arc of a circle so as to pass the reservoir in close proximity to one edge thereof thereby permitting excess ink in the arc portion of the shield to pass into said reservoir, means extending to the exterior of said compartment for tipping said reservoir, and means associated with the mounting of said ink reservoir for ventilating said compartment.

This specification signed this 15th day of July, 1924.

ERNEST J. BRASSEUR.
